UNITED STATES PATENT OFFICE.

HAZEN KIRKE BECKER AND EMIL G. JURGENS, OF CHICAGO, ILLINOIS, ASSIGNEES TO
PETERS MACHINERY COMPANY, OF CHICAGO, ILLINOIS, A CORPORATION OF
ILLINOIS.

CARTON-BLANK SEPARATOR.

Application filed August 14, 1925. Serial No. 50,260.

The main objects of this invention are to provide improved means for separating cards, carton blanks and the like from a stack whereby they may be fed to a machine 5 by which they are operated upon individually; to provide an improved separator of this kind whereby the cards may be lifted one at a time, from the top of the stack; to provide means for elevating the entire stack 10 in a step-by-step movement so as to bring the uppermost card in position to be acted upon by the separator; to provide improved means for automatically interrupting said elevating means to insure against a too rapid 15 feeding of the cards to the separator; and to provide means of this kind which is particularly adapted for use in separating cardboard blanks from a stack so as to permit them to be fed rapidly one at a time to mechanism which folds the blanks into cartons. 20

An illustrative embodiment of this invention is shown in the accompanying drawings, wherein:—

Fig. 1 is a front elevation of a separating machine to which this invention is applied, 25 part of the frame being broken away for the sake of clearness.

Fig. 2 is a side elevation of the same, taken from the right of Fig. 1.

Fig. 3 is a horizontal section taken on the 30 line 3—3 of Fig. 1.

Fig. 4 is a detail section showing the lifting mechanism, the view being taken on the line 4—4 of Fig. 3.

Figs. 5 and 6 are details in elevation of 35 the lifting mechanism.

Fig. 7 is a fragmentary vertical section taken on the line 7—7 of Fig. 1.

Figs. 8, 9 and 10 are details of the mechanism 40 which interrupts the feeding of the carriage to prevent choking of the machine caused by a too rapid feeding of the blanks to the separator.

In the specific construction herein shown, 45 the invention is applied to a machine wherein in a stack of carton blanks are fed, one at a time, to a mechanism which lines each blank with a sheet of lining paper and forms it into a carton. The folding and lining mechanism does not constitute a part of this 50 invention and a description thereof is believed to be unnecessary in this case. As herein illustrated, a stack of blanks is supported in a magazine by a vertically movable carriage

which is elevated step-by-step for locating the uppermost blank in position to be acted upon by the improved lifter which separates it from the remainder of the stack so as to permit it to be received by a conveyer which carries each blank separately to the lining and folding mechanism. In order to prevent the improved lifter from picking up more than the uppermost blank at each operation, which might occur upon a too rapid rise of the carriage, improved means is provided for 55 automatically interrupting the operation of the carriage elevating mechanism when the uppermost blank exceeds a predetermined height.

In the specific construction shown, the carriage 70 blank separator comprises an upright frame 1 having a vertically movable carriage 2 for supporting a stack of carton blanks 3 which are adapted to be elevated thereby in a step-by-step movement so as to 75 locate the uppermost blank in position to be acted upon by separating mechanism 4 which is adapted to deliver the blanks, one at a time, to a feeding and conveyer mechanism 5. 80

The frame 1 includes a pair of end bearing members 6 supported on posts 7 which are mounted on a base 8. Mounted on the base 8, are vertical guideways 9 which form a magazine for the stack of blanks 3. Arranged at the ends of the magazine, are vertical posts 10 mounted in socket members 11 and 12 for slidably supporting the carriage 2. 85

The carriage 2 is in the form of a plate 90 which fits within the guideways 9 and which is provided with bearing parts 13 slidably embracing the posts 10. The carriage 2 is fastened to one side of a pair of endless chains 14 which are driven by sprockets 15 fixed on a shaft 16 journaled in the frame 1. The chains 14 also pass around idlers 17 mounted on the socket members 11. The shaft 16 is suitably geared to a vertical shaft 17 on which is fixed a ratchet 18 100 adapted to be rotated by means of a pawl 19. The pawl 19 is carried by an arm 20 having a bearing part 21 at one end thereof of which loosely embraces the shaft 17. The other end of the arm 20 is hinged to a 105 rod or link 22 which is connected to a crank or arm 23 fixed on a drive shaft 24 which is journaled in the frame members 6. The

link 22 has a pin and slot connection 25 with the arm 23, which permits adjustment of the throw of the pawl 19 for controlling the distance through which the carriage 2 is elevated at each step. In order to permit the carriage 2 to be manually lowered after the last blank has been removed therefrom, a crank 16.1 is mounted on the shaft 16 and is adapted to be operatively connected thereto by means of a clutch 16.2. A handle 17.1 mounted on the upper end of the shaft 17 permits the carriage 2 to also be raised manually.

In the construction shown, the improved separating mechanism 4 includes a lifter 26 which is in the form of a bell crank lever fixed on a rock shaft 27 journaled in one of the frame members 6 and which is arranged for a limited axial movement. Mounted on one end of the lever 26, is a needle 28 and on the other end is a roller 29 which rides on a cam 30 fixed on a rotatable shaft 31 which is journaled in the frame member 6 adjacent the rocker shaft 27 and substantially parallel thereto. The bell crank lever 26 is heavier at its needle end than at its other end so that the needle is normally urged downwardly to penetrate the uppermost blank in the stack. During the downward movement of the needle, it is also moved transversely of the stack so as to force the needle to penetrate the blank at an incline. The transverse movement is imparted to the needle by a spring 32 which is secured to the outer end of the rocker shaft 27 and to the frame member 6, so as to shift the shaft 27 axially inwardly. The cam 30 is wide enough to permit the roller 29 to ride across its periphery during the axial movement of the bell crank lever arm 26. The rotatable cam 30 is arranged to lift the needle 28 for raising one end of the uppermost blank away from the remainder of the stack so as to permit it to be transferred to the conveyer. Also mounted on the rotatable shaft 31, is a second cam 33 which engages a roller 34 mounted on the outer end of the shaft 27 for retracting the rocker shaft against the action of the spring 27. The shaft 31 is driven by means of a chain 35 which engages a sprocket 36 fixed on the outer end of the shaft.

In the specific form shown, the separating mechanism also includes means for pushing the uppermost carton toward the conveyor when its end has been raised from the stack by the needle 28. As herein illustrated, this is accomplished by means of a pair of friction rollers 37 mounted on a shaft 38, journaled in the bifurcated end of an arm 39 which is pivoted to an arm 40 fixed on a rocker shaft 41. Mounted on the arm 39, is a pawl 42 arranged to engage a ratchet 43 fixed on the shaft 38 for locking the rollers 37 against rotation when the arm 39

is moved inwardly to urge the carton blank toward the conveyor. The shaft 41 is journaled in bearings 44 and has an arm 45 fixed on its outer end which is connected, by means of a rod 46, to a crank 47 which is fixed on a driven shaft 48 journaled in the frame. The arm 45 has a pin and slot connection 49 with the rod 46 so as to permit an adjustment of the throw of the arm 39. The shaft 48 is driven by the shaft 24 through a chain 50.

In order to prevent the lifter needle 28 from picking up more than the uppermost blank, means is provided for disengaging the pawl 19 from the ratchet 18 in the event that the uppermost blank in the stack exceeds a predetermined height. This momentarily interrupts the elevation of the carriage 2. The interrupting mechanism includes a bell crank lever 51 having an arcuate arm 52 which is located in position to hold the pawl 19 in an inoperative position when the lever 51 is rocked around its pivot. The arm 52 is sufficiently long to permit the pawl 19 to continue to move back and forth under the action of the rod or link 22 even when it is inoperative. The other end of the bell crank lever 51 is pivoted to the upper end of a link 53. The lower end of the link 53 is pivoted to the outer end of a lever arm 54 which is pivoted on the frame adjacent the upper end of the magazine. The inner end of the arm 54 carries a roller 55 which is adapted to ride on top of the stack of blanks so as to actuate the bell crank lever 51 when the uppermost blank exceeds a predetermined height.

In the specific form shown, the conveyer mechanism 5 includes a spiral conveyer 56 and a horizontal conveyer 57 arranged adjacent the magazine. The spiral conveyer 56 is mounted on a vertical axis and is driven by the shaft 48 through pinions 58 and 59. The spiral conveyer 56 is arranged to receive the separated blank from the lifter needle 28 and to elevate it still further so as to permit it to be transferred to the horizontal conveyer 57 which moves it to the folding mechanism, not shown.

As herein shown, the horizontal conveyer 57 comprises two sets of rollers 60 and 61 arranged one above the other so as to permit the blanks to pass between them. The lower set of rollers carries endless belts 62 on which the blanks are conveyed. The two sets of rollers are geared together by gears 63 and are driven by a chain 64.

In operation, a stack of the carton blanks is placed on the carriage 2 which moves upwardly, step-by-step, through the action of the pawl 19 and ratchet 18. The needle 28 is moved downwardly at an incline so as to penetrate the uppermost blank adjacent one end thereof. The needle is then raised by the action of the cam 30 so as to pick

up the end of the top blank and permit it to be transferred to the spiral conveyer 56. When the separated end of the blank approaches the top of the spiral conveyer, 5 the arm 39 moves inwardly so as to push the blank onto the horizontal conveyer. If the carriage 2 is elevated more than the thickness of a blank at each step, the arm 52 is shifted so as to momentarily interrupt 10 the operation of the elevating mechanism.

Although but one specific embodiment of this invention has been herein shown and described, it will be understood that numerous details of the construction shown may be 15 altered or omitted without departing from the spirit of this invention as defined by the following claims.

We claim:

1. A device of the class described comprising a magazine adapted to support a stack of cards, a horizontal conveyer located at one side of said magazine, lifting means adjacent the upper end of said magazine adapted to penetrate the uppermost card 25 and to separate a portion thereof from the stack, a second conveyer arranged to elevate said separated card portion to said horizontal conveyer, and means arranged to push the uppermost card onto said horizontal 30 conveyer while its said portion is elevated.

2. A device of the class described comprising a magazine adapted to support a stack of cards, a horizontal conveyer located at one side of said magazine, a lifter adapted 35 to penetrate the uppermost card for lifting one end thereof from the stack, a second conveyer arranged to elevate said separated card end to said horizontal conveyer, and means arranged to move the uppermost card 40 onto said conveyer while its one end is raised above the stack.

3. A device of the class described comprising a magazine adapted to support a stack of cards, a horizontal conveyer located 45 above and to one side of said magazine, a lifter adapted to separate one end of the uppermost card from the stack, a spiral conveyer arranged to elevate said separated card end to said horizontal conveyer, and means arranged to move the uppermost card onto said horizontal conveyer while its 50 said one end is elevated.

4. A device of the class described comprising a magazine adapted to support a stack of cards, a horizontal conveyor located above and to one side of said magazine, a lifter adapted to separate one end of the uppermost card from the stack, a spiral conveyer arranged to elevate said separated 55 card end to said horizontal conveyer, and a friction element arranged to push the uppermost card onto said horizontal conveyer while its said one end is elevated.

5. A device of the class described comprising a magazine adapted to support a

stack of cards, a horizontal conveyer located above and to one side of said magazine, a lifter needle adapted to penetrate the uppermost card for lifting one end thereof from the stack, a spiral conveyer arranged to elevate 70 said raised card end to said horizontal conveyer, and a friction element arranged to shift said uppermost card onto said horizontal conveyer while its one end is elevated. 75

6. A device of the class described comprising a vertically movable carriage for supporting a stack of cards, a substantially horizontal conveyer located above and to one side of said carriage, a lifter needle 80 adapted to penetrate the uppermost card for lifting one end thereof from the stack, means for raising said carriage to bring the uppermost card into position to be acted upon by said lifter, a spiral conveyer arranged to 85 elevate said raised card end to said horizontal conveyer, and a friction element arranged to move said uppermost card onto said horizontal conveyer while its one end is elevated. 90

7. A device of the class described comprising a magazine adapted for supporting a stack of cards, a needle arranged above said magazine, mechanism for moving said needle downwardly and transversely whereby said needle penetrates the uppermost card 95 at an incline thereto for lifting one end thereof from the stack, and means arranged to move the uppermost card to one side of said magazine while its one end is elevated.

8. A device of the class described comprising a magazine adapted for supporting a stack of cards, a lever arm pivotally mounted on a horizontal axis adjacent the upper end of said magazine, means for axially shifting said lever arm, other means 105 for simultaneously rocking said lever arm, a needle on the end of said lever arm arranged to penetrate the uppermost card for lifting one end thereof from the stack, and means arranged to move the uppermost card to one side of said magazine while its 110 one end is elevated. 100

9. A device of the class described comprising a magazine adapted for supporting a stack of cards, a bell crank lever arm pivoted on a horizontal axis adjacent the upper end of said magazine, a needle mounted on one end of said arm adapted to penetrate the uppermost card for lifting it from the stack, said one end being normally urged 115 downwardly, a spring arranged to shift said arm axially in one direction for moving said needle transversely during its downward movement, a cam arranged to retract said arm axially against the action of said spring, and another cam coacting with the other end 120 of said lever arm for lifting said one end and needle. 125

10. A device of the class described comprising a frame having a magazine for sup- 130

porting a stack of carton blanks, a rotatable shaft on said frame, a pair of cams mounted on said shaft, means for rotating said shaft, a rocker shaft supported in said frame and adapted for limited axial movement, a bell crank lever arm on said rocker shaft, a needle on one end of said arm and normally urged downwardly so as to penetrate the uppermost blank in the stack, a spring arranged to shift said rocker shaft axially in one direction during the downward movement of said needle, one of said

cams coacting with the other end of said lever arm for rocking said rocker shaft to lift said needle for separating the uppermost blank from the remainder of the stack, and a roller on said rocker shaft coacting with the other cam for retracting said lever arm against the action of said spring.

Signed at Chicago this 11th day of August, 1925.
